(57) **CLAIM**

The ornamental design for a connector socket, as shown and described.

DESCRIPTION

FIG. 1 is a top, front, right-side perspective view of a connector socket;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view taken along the line 8-8 shown in FIG. 6;

FIG. 9 is a cross-sectional view taken along the line 9-9 shown in FIG. 6; and,

FIG. 10 is a cross-sectional view taken along the line 10-10 shown in FIG. 6.

The broken lines depicted in the drawings illustrate portions of the connector socket that form no part of the claimed design.

1 Claim, 10 Drawing Sheets
